Primary Examiner — Cynthia M Chin(74) *Attorney, Agent, or Firm* — Young, Basile, Hanlon & MacFarlane, PC(57) **CLAIM**

The ornamental design for a drink cover, as shown and described.

DESCRIPTION

FIG. 1 is a front elevational view showing my new design, the rear side elevational view, left side elevational view and right side elevational views all being identical;

FIG. 2 is a plan view thereof;

FIG. 3 is a bottom elevational view thereof;

FIG. 4 is a top perspective view thereof;

FIG. 5 is a bottom perspective view thereof;

FIG. 6 is a cross-sectional view taken from line 6-6 in FIG. 1, showing the drink cover mounted on a mug;

FIG. 7 is another cross-sectional view thereof, showing the drink cover mounted on a wine/martini glass;

FIG. 8 is another cross-sectional view thereof, the drink cover mounted on a bottle; and

FIG. 9 is another cross-sectional view thereof, the drink cover mounted on a beverage glass.

The broken lines represent the environment in which the article is used and forms no part of the claim.
